Louis D Bartucci.

BY Richard B. Daven.

ATTORNEY.

UNITED STATES PATENT OFFICE.

LOUIS D. BARTUCCI, OF CHICAGO, ILLINOIS.

WATERPROOF CIGARETTE AND MATCH CASE.

Application filed July 26, 1927. Serial No. 208,618.

This invention appertains to tobacco user's appliances and more particularly to a novel cigarette and match case of a waterproof character adapted for wear with bathing suits.

One of the primary objects of the present invention is to provide a combined cigarette and match case having novel means for releasably connecting the cover of the case with the body thereof to form a waterproof connection therewith, so as to prevent the seeping of water and moisture into the case between the cover and body of the case, said means permitting the quick releasing of the cover when desired.

Another important object of the invention is the provision of novel means for detachably connecting the combined cigarette and match case with a belt, whereby the case can be conveniently worn by swimmers and the like.

A further object of the invention is the provision of a resilient U-shaped yoke for straddling the case carrying a loop for receiving the belt, with novel means for detachably connecting the resilient U-shaped yoke with the body of the case, whereby the case can be removed from the belt of the wearer independently of said yoke.

A still further object of the invention is to provide a waterproof cigarette and match case for swimmers which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed, and illustrated in the accompanying drawings, in which drawings:

Figure 1 is a side elevation of the improved cigarette and match case,

Figure 2 is an end view of the same, showing the cover partly broken away to illustrate the interior of the body of the case, the case being shown applied to a belt, the belt being in cross section.

Figure 3 is a side elevation of the complete case, and

Figure 4 is a longitudinal section through the case showing the arrangement of the various compartments therein for receiving matches, cigarettes and the like.

Referring to the drawings in detail, where-in similar reference characters designate corresponding parts throughout the several views, the letter A generally indicates the improved case which comprises a body 5 and a removable cover 6.

The cover 5 and the body 6 are preferably formed of sheet metal of a non-rusting character or the same can be formed of any other desired material. The body and cover can be suitably ornamented or colored to tone in with different colored bathing suits if so desired.

The body 5 includes an end wall 7, opposite front and rear walls 8 and 9, and side walls 10 and 11. The cover 6 is adapted to frictionally engage the body and includes a top wall 12 having a depending flange 13, which is adapted to fit over the walls 8, 9, 10 and 11 as clearly shown in Figure 4 of the drawings. It is preferred to have the flange 13 of a somewhat resilient nature so as to have a glove fit with the case when the cover is forced thereon, as will be now described.

The top wall 12 of the cover 6 is provided with a loop or strap 14 which hingedly carries an inwardly extending U-shaped bail 15 which straddles the body of the case. The extreme inner ends of the arms of the bail 15 can be provided with pivot lugs which are rockably mounted in ears 16 formed on the lower edges of the arms 17 of the operating yoke 18. These ears 16 are formed on the arms 17 intermediate their ends and the inner ends are connected with the walls 8 and 9 of the case by means of pivot pins 19. It is to be noted that the forward ends of the arms 17 are connected by a cross bridge piece 20 which can have an outstruck finger grip 21 formed thereon.

When it is desired to raise the cover 6 from off the body 5 it is merely necessary to grasp the finger grip 21 and swing the operating lever toward and over the wall 10. This is a cam action and lifts up on the bail 15 and forces the cover 6 from off of the case.

When it is desired to return the cover 6 on the body 5 the operating yoke is swung downward over the wall 7 and due to the cam action, the cover 6 will be effectively drawn down over the body. As the yoke swings past the longitudinal center of the body the bail 15 will have a tendency to draw the operating yoke 17 into intimate contact with

the wall 7 and thus the cover is firmly locked on the body 5 in friction tight contact therewith.

Arranged within the body 5 in contact with the wall 10 is a bent U-shaped strip of metal 23 which extends transversely of the body 5. The upper ends of the bent strip are preferably struck slightly inward, as at 24 for a purpose which will be later described. A 10 filler 25 is placed within the bent portion of the strip and prevents the collapsing thereof and this filler can be used for holding small articles such as rings and the like if so desired. However the strip with the body forms 15 means for receiving matches, while the main portion of the body at one side of the strip forms a compartment for receiving cigarettes. The filler 25 forms means for supporting the matches so that the same can be easily 20 grasped while the bent ends 24 of the strip hold the matches in place against accidental movement.

A match scratcher 26 of any character is placed on the inside of the cover 12 and suitable rivets 27 extend through the match scratcher, the wall 12 and the loop 14 for holding the loop 14 and the match scratcher 26 in an assembled position on the cover 6.

In order to permit the association of the case A detachably with a belt B I provide a resilient U-shaped yoke 30, which is preferably formed from a strip of sheet metal. This resilient yoke 30 includes resilient legs 31 and 32, and a connecting body portion 33 to which 35 is riveted a loop 34. The loop 34 receives the belt B as clearly shown in Figure 2 of the drawings.

In order to detachably connect the supporting yoke 30 with the case I provide studs 35 40 and 36 connected with the opposite sides of the body 5. The stud 35 is left smooth, while the stud 36 has its outer end reduced in diameter and externally threaded as at 37. The leg 31 of the yoke is provided with an outturned 45 end 38 and an opening 39 for receiving the stud 35, while the leg 32 is bent at right angles as at 40. The outer end of the leg 32 and the right angular portion 40 is slotted as at 41 for receiving the reduced threaded end 50 37 of the stud 36 and a thumb nut 42 is provided for fitting upon the threaded end of the

stud 36 and this nut is adapted to be threaded into binding contact with the leg 32 for holding the yoke against displacement.

When it is desired to remove the cigarette 55 case from the belt without displacing the yoke 32 it is merely necessary to remove the thumb nut 42 and pull out on the yoke 30 which will release the leg 32 from the stud, after which the leg 31 can be removed from 60 the stud 35.

From the foregoing description, it can be seen that I have provided a simple and compact cigarette and match case which is waterproof in its nature and which can be conveniently and readily associated with a belt of a bathing suit.

Changes in details may be made without departing from the spirit or the scope of this invention, but:

What I claim as new is:

1. A combined cigarette case and match box comprising a body, a cover adapted to frictionally engage the open end of the body, a loop carried by the cover, a U-shaped bail 75 hingedly carried by the loop and adapted to straddle the body, a cam yoke hingedly connected to the body at one side of the longitudinal axis thereof, and means hingedly connecting the rear ends of the arms of the bail 80 to the arms of the cam yoke intermediate the ends thereof.

2. A waterproof cigarette and match case comprising a body having an open end, a cover for said open end adapted to snugly 85 fit on the body, a loop carried by the cover, a U-shaped bail rockably carried by the loop at the transverse center of the cover and adapted to straddle the body of the case, a U-shaped cam yoke including side arms and 90 a connecting bridge portion, means hingedly connecting the inner ends of the arms to the body at one side of the longitudinal axis thereof, studs formed on the arms of the cam yoke intermediate the ends thereof, means hingedly 95 connecting the inner ends of the arms of the bail to the lugs, the bridge piece forming a stop for limiting the swinging movement of the cam yoke in two directions.

In testimony whereof I affix my signature.

LOUIS D. BARTUCCI.
